FEEDING DEVICE FOR SHAKER CONVEYERS

William W. Sloane, Chicago, Ill., assignor to
Goodman Manufacturing Company, Chicago,
Ill., a corporation of Illinois

Application October 17, 1946, Serial No. 703,816

6 Claims. (Cl. 198—220)

1

This invention relates to improvements in friction grip feeding devices for shaker conveyors of the type shown in my Patent No. 2,318,808, which issued May 11, 1943.

The principal objects of my invention are to provide a novel and simplified form of friction grip feeding device of the type utilizing holding cams to hold the feeding mechanism in position to automatically extend or retract an extensible trough of a shaker conveyor, which is of a more efficient and positive action than former feeding devices and is so arranged as to increase the effective feeding movement of the extensible trough during each stroke of the conveyor, by causing the friction gripping means to more positively move into disengaging positions upon the strokes of the conveyor opposite from the strokes which serve to extend or retract said extensible trough.

An application Serial No. 670,490, filed by me on May 17, 1946, now Patent No. 2,434,127, issued Jan. 6, 1948, relates to a feeding device for a shaker conveyor, utilizing holding cams to hold the feeding mechanism in position to extend or retract the extensible trough of a shaker conveyor, and having stops associated with the holding cams to more positively disengage the gripping means from the extensible trough of the conveyor on its strokes opposite from its feeding or retracting strokes. The device of my present invention, however, differs from that of my prior application in that a single stopping means is provided which is separate from the holding cams but is connected therewith to operate upon positioning of said holding cams in one operative position or another.

My invention may be more clearly understood as the following specification proceeds and with reference to the accompanying drawings wherein:

Figure 1 is a fragmentary plan view of the pick-up end of a shaker conveyor trough line having a feeding device constructed in accordance with my invention associated therewith;

Figure 2 is an enlarged fragmentary view in side elevation of the device shown in Figure 1, with certain parts thereof shown in substantially longitudinal section;

Figure 3 is an enlarged fragmentary transverse sectional view taken substantially along line 3—3 of Figure 1;

Figure 4 is an enlarged detail fragmentary longitudinal sectional view showing the feeding mechanism in position to extend the extensible trough of the conveyor;

Figure 5 is a fragmentary longitudinal sectional view somewhat similar to Figure 4, but

2

showing the feeding mechanism in position to retractably move the extensible trough of the conveyor;

Figure 6 is a fragmentary horizontal sectional view taken through the feeding device; and

Figure 7 is an enlarged exploded fragmentary isometric view showing the cams for operating the feeding device and the stopping means for positively disengaging the grip blocks from the extensible trough upon their strokes opposite from their feeding strokes.

In the drawings, a reciprocating trough 10 of a shaker conveyor is shown as having an extensible trough 11 nested therein and mounted for extensible and retractable movement with respect thereto. Said reciprocating trough may be connected to and extend forwardly from a swivel (not shown) of a shaker conveyor trough line, for continuously conveying material from said reciprocating trough to the trough line when said reciprocating and extensible troughs are at various angles with respect to the trough line, and may be reciprocably driven from said trough line through said swivel in a well known manner and not herein shown or described.

The reciprocating trough 10 is slidably supported adjacent its forward end on bearing plates 12, 12 extending along and projecting laterally from the upper flanges of said extensible trough on bearing blocks 13, 13. Said bearing plates 12, 12 extend between said bearing blocks 13, 13, and said bearing blocks are pivotally mounted on the inside of vertical side walls 14, 14 of a frame 15 projecting forwardly from and extending across the bottom of and upwardly along opposite sides of said reciprocating trough. Said extensible trough has a gathering shovel 16 on its forward end and is slidably supported on the ground on the forward end of said shovel, and may be supported above the ground at its rear end on a supporting shoe (not shown), in a manner well known to those skilled in the art.

The means for extensibly or retractably moving the extensible trough relative to the reciprocating trough is similar to that shown in my prior Patent No. 2,318,808, and includes two pairs of friction grip blocks 25, 25 adapted to engage the upper and lower sides of the bearing plates 12, 12. Each pair of said grip blocks is pivotally mounted in a carrier member 26. Two laterally spaced connecting frames 27, 27 project forwardly from and are transversely pivoted to the lower forward end of the frame member 15 on transverse shafts 28, 28 mounted at their ends in laterally spaced side walls 29 and 30 projecting upwardly from said

frames adjacent opposite sides thereof. Said connecting frames form a means for connecting said carrier members to said reciprocating trough, as in my Patent No. 2,318,808. Said carrier members and their connection to said reciprocating trough and the mechanism for exerting forces on opposite ends of said carrier members to engage said grip blocks with said bearing plates during alternate strokes of the conveyor, are the same for each side of said extensible trough, so a description thereof for one side of said extensible trough will suffice for both sides of said trough.

A yieldable link 33 connects the lower end of each carrier member 26 with the connecting frame 27. Said link includes a rod 34 secured to a forward upright end wall 35 of a yoke 36 at one of its ends and slidably mounted in a pivotal pin 37 at its opposite end. Said pivotal pin 37 is transversely pivoted to the lower end of said carrier member. A compression spring 39 encircles said rod and is interposed between the forward side of said end wall 35 and a flanged sleeve 40, slidably mounted on said rod and abutting said pivotal pin (see Figures 2 and 6). Said compression spring is of such strength that said yieldable link will normally be a solid member, but will yield upon the engagement of an obstruction by the shovel 16 upon the forward strokes of the conveyor, to disengage the grip blocks 25, 25 from the bearing plate 12 and prevent buckling of the trough line.

The yoke 36 is mounted between the side walls 29 and 30 of the connecting frame 27 on the lower ends of two longitudinally spaced rocking links 43 and 44 (see Figure 2). Said links are pivotally mounted between said side walls on parallel longitudinally spaced transverse shafts 45 and 46, respectively, mounted at their ends in said side walls.

The yoke 36 is provided with a depending lower shouldered portion 47 which is adapted to engage an engaging face 49 of a stopping member 50, pivotally mounted adjacent its opposite ends in the side walls 29 and 30 of the connecting frame 27, for movement with respect thereto about a transverse axis. When said shouldered portion 47 of said yoke is held in position to engage said engaging face 49, as will hereinafter more clearly appear as this specification proceeds, the yieldable link 33 will exert a forward thrusting action on the lower end of the carrier member 26 during the forward strokes of the conveyor. Upon the return strokes of the conveyor said engaging face 49 of said stopping member 50 will engage the shouldered portion 47 of said yoke and form a reaction member for the link 33, and positively move said link with said connecting frame. This in turn will positively pivot said carrier member about the pivotal pin 37 in a direction to release the grip blocks 25, 25 from said bearing plate 12. Clearance is provided between said engaging face and said shouldered portion during the forward strokes of the conveyor to permit said stopping member to be readily moved into an engaging or disengaged position.

The upper end of the carrier member 26 is connected with the connecting frame 27 by means of a link 54 pivotally connected between the furcations of a rearwardly and upwardly projecting bifurcated ear 55 of said carrier member. The end of said link opposite from said carrier member is pivotally connected to the upper end of a rocking member 56. Said rocking member is pivotally mounted on the transverse shaft 46 and has a bifurcated arm 57 depending therefrom, which has a forwardly facing abutment surface 58 at the

lower end of each of its furcations. Said abutment surfaces are adapted to engage a rearwardly facing engaging face 59 of the stopping member 50. The angle of said engaging face 59 with respect to the engaging face 49 is such that when said face 59 is in position to engage said abutment surfaces 58, 58, said engaging face 49 will be out of position to be engaged by the shouldered portion 47 of the yoke 36, and will permit said yoke to move relatively freely with respect to the connecting frame 27 about the links 43 and 44. Clearance is provided between said engaging face and the abutment surfaces 58, 58, to permit ready movement of said stopping member into its several operative positions. When said depending arm and abutment surfaces 58, 58 are held in position to be engaged by said engaging face 59, as will hereinafter more clearly appear as this specification proceeds, said link 54 will exert a pulling force on the upper end of said carrier member during the return strokes of the conveyor. Upon the forward strokes of the conveyor said engaging face 59 will engage said abutment surfaces and exert a pushing force on the upper end of said carrier member, to positively release said grip blocks from said bearing plate.

A compression spring 77 is provided to yieldably hold the rocking member 56 and yoke 36 in position to hold the carrier member 26 in the proper position of inclination with respect to the bearing plate 12, so the grip blocks 25, 25 will be in position to engage said bearing plate 12 at the beginning of the forward or return strokes of the conveyor, depending upon whether it is desired to extend or retract the extensible trough 11. Said spring is interposed between an arm 78 extending angularly inwardly and downwardly from the link 43 and an arm 79 extending angularly upwardly and forwardly from the rocking member 56, and is not strong enough to cause any gripping action of the grip blocks 25, 25, but merely serves to yieldably hold the carrier member in position so said grip blocks may engage the bearing plate 12 at the beginning of the feeding strokes of the conveyor.

Two cams 60 and 61 are provided to selectively hold either or both of the links 33 and 54 for movement with the connecting frame 27 during reciprocation of the conveyor to cause extensible or retractile movement of said extensible trough, or to cause reciprocable movement of said extensible trough with said reciprocating trough. Said cams are herein shown as being formed integrally with a common sleeve 62, freely mounted on a transverse shaft 63 journaled in opposite upright side walls 51, 51 of the connecting frame 27 (see Figures 6 and 7).

The cam 60 is adapted to engage a roller 64 mounted between the sides of the yoke 36 adjacent its rear end on a pivotal pin 65, to move and hold said yoke in position to be engaged by the engaging face 49 of the stopping member 50 upon the return strokes of the conveyor.

The cam 61 is adapted to engage a roller 66 mounted between the furcations of the depending arm 57 of the rocking member 56 on a pivotal pin 67, to move and hold the abutment surfaces 58, 58 of said arm into position to be engaged by the engaging face 59 of the stopping member 50 upon the forward strokes of the conveyor.

The cams 60 and 61 are moved into engaging or disengaged positions by a hand lever 69 keyed on the outer end of the transverse shaft 63. A yieldable operating connection indicated generally by reference character 70 is provided be-

tween said shaft and the sleeve 62, to operate said cams from said shaft and relieve said hand lever from sudden shocks during movement of said cams from one operative position to another during operation of the conveyor. Said yieldable operating connection is clearly shown and described in my Patent No. 2,318,808 and is no part of my present invention so need not herein be described in detail.

The angular positions of the cams 60 and 61 with respect to the sleeve 62 are such that when the hand lever 69 is in the upright position shown in Figure 2, both of said cams will engage their respective rollers to cause the links 33 and 54 to reciprocably move with the connecting frame 27 during the forward and return strokes of the conveyor and reciprocably move the extensible trough 11 with the reciprocating trough 10. When said hand lever is in the forwardly inclined position shown in Figure 4, the cam 60 will be moved into engagement with the roller 64 and the cam 61 will be moved out of engagement with the roller 66 and forces will be exerted on the yieldable link 33 to engage the grip blocks 25, 25 with the bearing plate 12 during the forward strokes of the conveyor and to disengage said grip blocks from said extensible trough during the return strokes of the conveyor, to extensibly move said extensible trough with respect to said reciprocating trough.

When said hand lever is in the rearwardly inclined position shown in Figure 5, the cam 61 will be moved into engagement with the roller 66 and the cam 60 will be moved out of engagement with the roller 64 and forces will be exerted on the rocking arm 56 and link 54, to engage the grip blocks 25 with the extensible trough during the return strokes of the conveyor and to release said grip blocks from said extensible trough during the forward strokes of the conveyor, to retractibly move said extensible trough with respect to said reciprocating trough.

The shafts 63, 63 on opposite sides of the feeding mechanism are connected to operate together by means of flexible couplings 71, 71 connected to the inner ends of said shafts, and connected together by means of a transverse shaft 73.

The connection between the hand lever 69 and the stopping member 50, for moving said stopping member into position so its engaging face 49 will move into position to engage the shouldered portion 47 of the yoke 36 and its engaging face 59 will move into a disengaged position with respect to the depending arm 57, and vice versa, includes a link 80 pivotally connected intermediate the ends of said hand lever at one of its ends. The opposite end of said link is pivotally connected with a rocking arm 83, secured to and projecting upwardly from the outer end of a shaft 84 formed integrally with and projecting outwardly from said stopping member. Upon movement of said hand lever into position to engage the cam 60 with the roller 64 on the yoke 36, the engaging face 49 of the stop 50 will be moved into position to engage the shouldered portion 47 of said yoke upon the return strokes of the conveyor. This will positively move said yoke with the connecting frame 27 and break the gripping connection between the grip blocks 25, 25 and the bearing plate 12. At the same time, the engaging face 59 of said stopping member 50 will be moved out of engagement with the depending arm 57 of the rocking member 56, to permit relatively free movement of said rocking member about the axis of the shaft 46, so

the yieldable link 33 can more readily move the carrier member 26 into position to engage the grip blocks 25 with the bearing plate 12 during the forward strokes of the conveyor and in a direction to positively disengage said grip blocks from said bearing plate during the return strokes of the conveyor, and effect forward feeding movement of the extensible trough for substantially the full lengths of the forward strokes of the conveyor.

When the hand lever 69 is moved into the position shown by broken lines in Figure 5 and the cam 61 is in engagement with the roller 66, the engaging face 49 of the stopping member 50 will be disengaged from the yoke 36 and the engaging face 59 of said stopping member will be moved in position to engage the depending arm 57 of the rocking member 56. This will cause positive movement of said rocking member and link 54 with the connecting frame 27 during the forward and return strokes of the conveyor, and will permit relatively free movement of the yieldable link 33 with respect to said connecting frame 27 about the links 43 and 44 during both the forward and return strokes of the conveyor, to positively break the gripping connection between the grip blocks 25, 25 and the bearing plate 12 at the beginning of the forward strokes of the conveyor and assure gripping of said grip blocks with said bearing plate for substantially the full lengths of the return strokes of the conveyor, and the release of said grip blocks from said bearing plates for substantially the full lengths of the forward strokes of the conveyor, to retractibly move the extensible trough 11 for substantially the full length of each return stroke of the conveyor.

It may be seen from the foregoing that a novel form of stopping means for the links 33 and 54 has been provided, which is separate from the holding cams 60 and 61 and is operable upon operation of said holding cams, to cause positive movement of the link acting as the feeding link, during the strokes of the conveyor opposite from which said link is moved by its respective holding cam, and permitting the other link to be relatively free to move with respect to the connecting frame 27, to assure positive engagement and disengagement of the grip blocks during alternate strokes of the conveyor, for substantially the full lengths of the strokes thereof, when extensibly or retractibly moving said extensible trough with respect to said reciprocating trough.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a feeding mechanism for shaker conveyors and in combination with an extensible trough having a shovel on its forward end, a reciprocating trough, a connecting frame transversely pivoted to said reciprocating trough, a carrier member, friction gripping means carried by said carrier member for engagement with said extensible trough during alternate strokes of the conveyor, to extensibly or retractibly move said extensible trough with respect to said reciprocating trough, a link pivotally connecting one end of said carrier

member with said connecting frame, another link pivotally connecting the opposite end of said carrier member with said connecting frame, two spaced holding cams, each of said cams being selectively operable to hold one of said links for positive movement with the conveyor during alternate strokes of the conveyor and cause said link to exert a force on said carrier member to engage said grip blocks with said extensible trough during alternate strokes of the conveyor, and a stopping means for each of said links, operable upon the strokes of the conveyor opposite from the extending or retracting strokes thereof to positively disengage said gripping means from said extensible trough, said stopping means being selectively movable into position to serve as a stop for the link positively moved by one of said respective cams and to permit relatively free movement of said other link.

2. In a feeding mechanism for shaker conveyors and in combination with an extensible trough having a shovel on its forward end, a reciprocating trough, a connecting frame transversely pivoted to said reciprocating trough, a carrier member, friction gripping means carried by said carrier member for engagement with said extensible trough during alternate strokes of the conveyor, to extensibly or retractably move said extensible trough with respect to said reciprocating trough, a link pivotally connecting one end of said carrier member with said connecting frame, another link pivotally connecting the opposite end of said carrier member with said connecting frame, two spaced holding cams, each of said cams being selectively operable to cause one of said links to positively move with the conveyor during alternate strokes of the conveyor and cause said link to exert a force on said carrier member to engage said grip blocks with said extensible trough during alternate strokes of the conveyor, and a stopping means for said links, operable upon the strokes of the conveyor opposite from the strokes that said holding cams move said respective links with the conveyor, said stopping means being movable into position to serve as a stop for the link positively moved by one of said respective cams to positively release said gripping means upon the strokes of the conveyor opposite from its feeding strokes, and to permit relatively free movement of said other link, including a member pivotally mounted on said frame and having one engaging face adapted to serve as a stop for one link and another engaging face disposed at an angle to said first mentioned engaging face and adapted to serve as a stop for said other link, and movable into position to disengage one of said engaging faces when said other engaging face is moving into an engaging position.

3. In a feeding mechanism for shaker conveyors and in combination with an extensible trough having a shovel on its forward end, a reciprocating trough, a connecting frame transversely pivoted to said reciprocating trough, a carrier member, friction gripping means carried by said carrier member for engagement with said extensible trough, during alternate strokes of the conveyor, to extensibly or retractably move said extensible trough with respect to said reciprocating trough, a link pivotally connecting one end of said carrier member with said connecting frame, another link pivotally connecting the opposite end of said carrier member with said connecting frame, two spaced holding cams, each of said cams being operable to cause one of said links to positively move with the conveyor, and cause said link to exert a

force on said carrier member to engage said grip blocks with said extensible trough during alternate strokes of the conveyor, to extensibly or retractably move said extensible trough with respect to the conveyor, a member transversely pivoted to said frame and having one engaging face adapted to serve as a stop for one link and positively release said gripping means upon the strokes of the conveyor opposite from its feeding strokes, and another engaging face disposed at an angle to said first mentioned engaging face and adapted to serve as a stop for said other link, and so arranged that as one of said engaging faces moves to an engaged position, the other of said engaging faces will move to a disengaged position and permit relatively free movement of its associated link with respect to said connecting frame, a hand lever for moving said cams into position to cause either one of said links to positively move with said reciprocating trough, and an operative connection between said hand lever and said stop to pivotally move said stop into one operative position or another, upon movement of said cams into one operative position or another.

4. In a feeding mechanism for shaker conveyors, a reciprocating trough, an extensible trough, a connecting frame extending in advance of and transversely pivoted to said reciprocating trough, a carrier member, friction gripping means carried by said carrier member and adapted to engage said extensible trough during alternate strokes of the conveyor, a link connecting the lower end of said carrier member with said connecting frame, another link pivotally connected to the upper end of said carrier member, a rocking member transversely pivoted to said connecting frame, and having pivotal connection with said other link, and means selectively operable to hold either of said links for movement with said connecting frame in the directions of reciprocation of the conveyor including two spaced holding cams transversely pivoted to said frame and selectively operable to engage either said rocking member or said yieldable link, or to simultaneously engage both said rocking member and said yieldable link, to engage said gripping means with said extensible trough during alternate strokes of the conveyor, and a stopping means on said frame separate from said holding cams and movable into position to serve as a stop for the link which acts as a feeding member, and acting in a direction opposite from the respective cam engaging said link to positively release said gripping means upon the strokes of the conveyor opposite from its feeding strokes, and permitting relatively free movement of said other link with respect to said connecting frame.

5. In a feeding mechanism for shaker conveyors, a reciprocating trough, an extensible trough, a connecting frame extending in advance of and transversely pivoted to said reciprocating trough, a carrier member, friction gripping means carried by said carrier member and adapted to engage said extensible trough during alternate strokes of the conveyor, a link connecting the lower end of said carrier member with said connecting frame, another link pivotally connected to the upper end of said carrier member, a rocking member transversely pivoted to said connecting frame, and having pivotal connection with said other link, and means selectively operable to hold either of said links for movement with said connecting frame in the directions of reciprocation of the conveyor including two spaced holding cams transversely pivoted to said frame on one

side of said rocking member, and a stopping member transversely pivoted to said frame on the opposite side of said rocking member from said holding cams, said stopping member having one engaging face adapted to serve as a stop for said one link, to cause said link to positively release said friction gripping means upon the return strokes of the conveyor, and having another engaging face disposed at an angle to said first mentioned engaging face and adapted to serve as a stop for said other link to positively release said friction gripping means upon the forward strokes of the conveyor upon movement of respective of said holding cams into position to cause retraction of said extensible trough, each of said stops moving out of a stopping position upon movement of the cam associated therewith to an inoperative position, to permit relatively free movement of the link which is not exerting a feeding force on said carrier member during both the forward and return strokes of the conveyor.

6. In a feeding mechanism for shaker conveyors, a reciprocating trough, an extensible trough, a connecting frame extending in advance of and transversely pivoted to said reciprocating trough, a carrier member, friction gripping means carried by said carrier member and adapted to engage said extensible trough during alternate strokes of the conveyor, a link movably connecting the lower end of said carrier member with said connecting frame, another link pivotally connected to the upper end of said carrier member, a rocking member transversely pivoted to said connecting frame, and having pivotal connection with said other link, and means selectively operable to hold either or both of said links from movement with respect to said connecting frame in the directions of reciprocation of the conveyor

to cause either of said links to engage said grip blocks with said extensible trough including two spaced holding cams transversely pivoted to said frame on one side of the axis of rocking movement of said rocking member, a hand lever for selectively moving said cams into position to hold either of said links for movement with said connecting frame, a stopping member transversely pivoted to said frame forwardly of the pivotal axis of said rocking member, said stopping member having one engaging face adapted to be engaged by said rocking member and serve as a stop for said link connected thereto during the forward strokes of the conveyor, upon engagement of an associated cam with said rocking member, to positively release said friction gripping means upon the forward strokes of the conveyor, and having another engaging face disposed at an angle to said first mentioned engaging face and adapted to serve as a stop for said first mentioned link upon the holding of said link from movement with respect to said connecting frame by the other of said cams, to positively release said gripping means upon the return strokes of the conveyor, said stops moving to a disengaged position upon movement of the cams associated therewith to disengaged positions, to permit relatively free movement of the link which is not exerting a feeding force on said carrier member, during both the forward or return strokes of the conveyor, and an operative connection between said hand lever and said stopping member for pivotally moving said stopping member into one operative position or another upon movement of either of said cams to an operative position.

WILLIAM W. SLOANE.
